UNITED STATES PATENT OFFICE.

CLARENCE M. ANDERSON, OF OKLAHOMA CITY, OKLAHOMA.

PREScription-FILING CABINET AND THE LIKE.

Application filed August 2, 1927. Serial No. 210,158.

My invention relates to filing cabinet and perforator for prescriptions, and the like.

The object of my invention is to produce a device of the character described which will be new, novel, efficient, and of utility; which will be compact, substantial, cheap and durable; which will provide a private filing cabinet which can be kept away from the public and which will be easily accessible to the pharmacist, druggist, or operator and which will occupy little space and can be easily kept on a counter, desk, or table.

With these and other objects in view my invention consists in the construction, novel features, and combination of parts herein-after more fully described, illustrated in the accompanying one-sheet drawing; and pointed out in the claims hereto appended; it being understood that various changes in the form, proportion, size, shape, weight and minor details of construction, within the scope of my invention may be resorted to without departing from the spirit or principle of the invention or sacrificing any of the advantages thereof.

The novel features, invention and other objects will be more fully shown in the specification, claims, and accompanying one-sheet drawing, of which,

Figure 1 is a perspective view of the cabinet open and empty; Fig. 2 is a perspective view of the perforator for the prescriptions; Fig. 3 is a perspective view of the open filing cabinet showing in the middle portion a number of prescriptions held up by the holding or lifting arm.

Like characters of reference designate like parts in all the figures.

The method of handling the prescriptions, which of necessity are on file for long periods of time if not practically perpetually has been unsatisfactory. This is largely by reason of the fact that they are made by various physicians throughout the country on different size sheets of paper and sometimes are folded and sometimes not and are handled by various persons before they reach the druggist for filing and filling. Oftentimes a prescription is desired to be filed immediately on account of the urgency for the necessity of it; practically no way of indexing or consecutively numbering is applicable for filing such prescriptions. My invention relieves all of the objections to such a careless and slipshod manner of handling, besides making it possible to easily handle them and

easy to get hold of any given number of prescriptions desired; it also makes it possible to file many more prescriptions in the same size filing cabinet than is permitted by any other method.

Referring to the drawing wherein for the sake of illustration is shown a preferred embodiment of the invention, I provide a metallic, or other suitable material, filing cabinet 65 adapted to be placed upon a table, counter, or desk 1; the cabinet has preferably an extended beveled base 3 at the bottom of the filing cabinet 2 and can be when desired securely fastened to the table or other fixture as shown 70 at 4. Said filing cabinet has a side 5, a back 6, a second side 7, a top 8, a door 9, and an inside bottom 10. These are all preferably of metal, but may be made of other suitable material. In the base 10 is provided a plurality 75 of struck-up tongues 14 adapted to receive and hold the bent wire base 13 of filing rod 11 having a sharp point at its upwardly extending free end 12. This filing rod is preferably of coppered spring steel, the spring 80 steel being sufficiently pliable to allow of bending, but permitting it to keep its form and place; the coppering being intended to prevent its being rusted or tarnished and to make the surface thereof at all times smooth 85 for the easy manipulation upwardly and downwardly thereon of a plurality of prescriptions on file. The sharp point 12 is preferably a sufficient distance from the top of the inside of the filing cabinet to permit the insertion of the hands of the operator and the taking therefrom and placing therein of a large number of prescriptions when it is desired to be done. The door 9 is preferably 90 hung on cleat hinges 15 at the bottom and 16 near the top mounted on rod 17 extending from the base 10 to the top 8 which is anchored to said base and top respectively. Said door has near its outer closing edge a lock 21 adapted to be locked securely to said 95 side-wall 5 and to be unlocked at any time the operator desires to use the same. Said rod 17 has floatably anchored thereon preferably a steel holding or lifting arm 18 with a rubber tip 19 near its outer end; said arm is adapted 100 to be normally kept inside of the wall 7 and also to be partially turned away from said wall in a position adjacent said filing rod 11 as best shown at 20. This arm is adapted to hold up prescriptions away from the other 105 prescriptions filed therebelow as shown at 32 and to keep them in a given position until the 110

prescription 31 is read, or copied, or taken out, as the case may be; after which time the prescriptions so lifted and held can be permitted to descend on rod 11 after the withdrawal of arm 18 thereunder. When a prescription is presented to the pharmacist, or druggist, or operator which has not theretofore been filed in this filing cabinet it is first perforated. For this purpose I provide a perforator composed of an under surface plate 22 preferably adapted to be installed on the top of said cabinet, said under surface plate having an upstanding stud or button 28 at its front center. A perforating plate 25 bent forwardly under surface plate 22 at their inside juncture at edge portion 23 so as to create a resilience for said perforating plate, said perforating plate is preferably triangular and forms a tongue at its apex 26. A disc 29 is fastened adjacent said apex 22 and has connected thereto a hollow cutting member 30 being adapted to perforate with its cutting point each prescription when said prescription is pressed down on stud or button 28 after having been inserted between under plate 22 and perforating plate 25 and against upstanding side edge 24 and against inside edge portion 23. When disc 29 is pressed downwardly and the prescription is perforated the resilience between said under plate 22 and said perforating plate 25 formed by the bend at the inside edge portion 23 causes said perforating plate 25 to again resume its normal position for the further inserting of prescriptions therein for perforation. Said cutting member 27 is placed on said perforator at a point equally distant from the top of the prescription as the filing rod is distant from the back 6 of the filing cabinet. When the prescription is placed in the said perforator as indicated and the disk on 29 on cutting member 30 is pressed down on upstanding stud 28 a clean cut perforation is cut in the prescription and it is then ready to be threaded over said filing rod 11. It will be seen that the top and left side edges of the prescription may be the same as the top and left side edges of the other prescriptions whether the prescription so filed is as large as the general average of prescriptions on file or not. The perforation being clean cut and taking out a small portion of the paper without permitting the edges from being wrinkled and bent upwardly and downwardly permits the prescriptions to be lowered and raised on the file rod much more easily and permits of the filing of a greater number of prescriptions in a given space than would be possible if the prescriptions were not perforated uniformly and in a clean cut manner, and permits the prescriptions to be more easily removed from the file. The first prescriptions filed would be at the bottom and they would be gradually built up consecutively therefrom the last and highest

number being at the top. The number of the prescription to be refilled would be handed to the pharmacist, or druggist, or operator and the number on the file rod would be sought and when found the prescriptions thereabove would be lifted and the holding or lifting arm partially turned to be placed thereunder thereby holding it away from the prescription desired. When the operator is through with the prescription the arm would then be withdrawn and placed in a normal position along the inside of wall 7 and the prescriptions formerly held thereabove would be lowered on the filing rod in regular order without taking any of the prescriptions off of the filing rod.

Having described my invention what is claimed and desired to be secured by Letters Patent is:

1. A cabinet of the character described, comprising an upright metallic case having walls, top, bottom; and a door, said door being adapted to be locked; said bottom being adapted to be fastened to a base, and having on its inside a plurality of upstanding tongues; a filing rod having its lower end bent so as to form a base and to be removably held in said tongues, its upper free end being pointed and adapted to be used through perforations in prescriptions, and the like; a rod anchored at top and bottom adjacent one front edge of said cabinet and being adapted to hinge said door thereon, a slideable arm being adapted for movement and for positioning on said anchored rod for separating, holding and raising one portion of said prescriptions from the other portion; in combination with a suitable cutting perforator adapted to perforate papers for filing in said cabinet so as to make their filing therein uniform; said filing rod and the prescription and the like placed therein being adapted to be removed from said cabinet and retired to a suitable container.

2. A filing cabinet of the character described, comprising four walls including a door adapted to be locked; a top and bottom; a rod anchored to said top and bottom near one front corner adapted to pivot the hinges of said door near its top and bottom; a slideable arm having a rubber button on its outer end being slidably anchored on said anchored rod; a spring-steel filing rod bent at its bottom to form a base, said base being adapted to be held by tongues in the inside of said bottom; the upper end of said rod being pointed; said filing rod being adapted for receiving and holding said prescriptions thereon, in combination with a suitable perforator being adapted to be attached to the top of said cabinet, and adapted to perforate prescriptions and the like for uniformly filing in said cabinet.

CLARENCE M. ANDERSON.
